United States Patent Office.

C. W. STROUT AND AMOS WILDER, OF HALLOWELL, MAINE.

Letters Patent No. 93,135, dated July 27, 1869.

IMPROVED MACHINE FOR VARNISHING FLOOR OIL-CLOTH.

The Schedule referred to in these Letters Patent and making part of the same.

Be it known that we, C. W. STROUT and AMOS WILDER, of Hallowell, in the county of Kennebec, State of Maine, have invented a new and useful Machine for Varnishing Floor Oil-Cloth or other fabric; and we do declare that the following is a full, clear, and exact description of the construction and operation of the same, reference being had to the annexed drawings, which make a part of this specification, in which—

Figure 1 represents a general view of the varnishing-machine in perspective.

Figure 2, a longitudinal section, showing the platform under the brushes.

A A, fig. 1, is a frame, enclosing an adjustable frame, B B.

C C is a lever-frame, attached to the frame B B by rods D D, having its fulcra at E E.

F is a cylindrical, horizontal brush, attached to frame B B, on the end of which is pulley G.

H H are longitudinal brushes, attached to arms I I.

J is a shaft, to which are attached pulleys K L.

M is a belt, leading from pulley K to pulley N, on shaft O.

P is a belt, leading from pulley L to pulley G.

Q Q, fig. 2, are metallic rods, attached to frame A A, and situated beneath brushes F and H H.

R is a button, used to hold the frame B B in position.

S is a roll, from which the oil-cloth or other fabric is delivered.

To enable others to use our invention, we will proceed to describe its operation.

The fabric to be varnished is passed, from the roll S, under the brushes H H and F, and is supported by the metallic rods Q Q. A stream of varnish is now allowed to flow, from a reservoir or sprinkler, to the fabric, in front of brushes H H. The button R is now released, allowing the lever-frame C C to turn on its fulcrum E, when the frame B B descends, bringing the brushes in contact with the fabric T. Motion is now given to crank U, and transmitted, through shaft Y, pulleys K L, and belts P M, to brushes H H and F. The fabric is now drawn steadily along, the brushes coming in contact with the varnish, and spreading it evenly, till the whole piece has received a uniform finish. The lever-frame C C is now depressed, raising frame B B. Button R is now thrown into place, when the machine is ready to receive another piece of goods.

Claim.

What we claim, and desire to secure by Letters Patent, is—

The mode of applying varnish to oil-cloth or other fabrics, by means of horizontal, rotary, and cylindrical brushes, separately or in combination, substantially as described and set forth.
